STAMP FEEDING AND GLUING MECHANISM

Clarence J. Malhiot, Oak Park, Ill., assignor to
 F. B. Redington Co, Chicago, Ill., a corporation
 of Illinois

Application June 2, 1939, Serial No. 276,986

15 Claims. (Cl. 91—51)

The present invention relates to a stamp, label or strip feeding and gluing mechanism and more particularly to such a mechanism for use in applying a stamp, label or strip to a pre-determined portion or end of an article or package. In prior devices of this character with which applicant is familiar, the erroneous withdrawal of more than one stamp, label or strip from the feed magazine or stack is rather commonly encountered. This erroneous feeding of more than one strip at a time interferes with the proper operation of the feeding mechanism, the gluing mechanism and the package applying mechanism, and represents a considerable loss of money in the destruction of tax stamps when employed for the feeding and applying of tax stamps to packages such as packages of tobacco.

Another rather common failure of such prior devices is the failure of the withdrawing mechanism to withdraw a stamp, label or strip from the magazine, and this failure of the withdrawing mechanism means that packages are rather commonly passed through the wrapping machine without having a stamp, label or strip attached thereto, and such packages must either be refed through the wrapping machine or else discarded entirely.

Other difficulties encountered in feeding the strips past the gluing mechanism or rollers are due to the tendency of the stamps, labels or strips to adhere to the glue rolls or for other reasons to be torn or mispositioned in their feeding mechanism as they are brought into or past the gluing mechanism, this resulting in the destruction of the stamps, labels or strips, or the mispositioning of the same upon the article or package.

It is accordingly an object of this invention to provide a mechanism for feeding stamps, labels or strips from a magazine or stack to a predetermined position for association with an article or package, and during such feeding to apply adhesive thereto, which mechanism is simple in construction and avoids the defects and insufficiencies of the prior devices.

The claims presented in the present case relate essentially to the glue applying means, and to the mechanisms and strip feeding means more intimately associated therewith. Claims to the hopper structure for the strips, and to the mechanisms and feeding devices more directly associated therewith are presented in a divisional application.

Among the more specific objects relating to the glue applying means and associated mechanisms

is to provide in a stamp feeding and adhesive applying mechanism a gluing device having stamp feeding means separate from the gluing means and in which the glue cannot pass to or accumulate upon the feeding means.

It is also an object of the invention to provide in a feeding and gluing mechanism a glue applier between which and the stamp, label or strip there will be no relative motion during the application of the glue to the stamp and in which feeding means are provided for withdrawing the stamp, label or strip from the glue applier in a direction and at a speed such that the glue applier will exert no retarding effect on the feeding of the stamp, label or strip.

A still further object of the invention is to provide improved gluing mechanism for applying glue or adhesive to stamps, labels, or strips, and to provide in combination therewith improved feeding means whereby to propel the stamps, labels, or strips through the gluing mechanism in a proper and reliable manner.

Other and further objects and advantages of the invention will be apparent from the following description when taken in connection with the accompanying drawings wherein:

Fig. 1 is a plan view of a machine having stamp feeding and gluing mechanism embodying the invention.

Fig. 2 is a fragmentary vertical section taken along the line 2—2 of Fig. 1.

Fig. 3 is an end view in elevation of the mechanism of Fig. 1 taken from the right of said Fig. 1.

Fig. 4 is a fragmentary view in perspective illustrating the withdrawal of a stamp from a stack of stamps.

Fig. 5 is a view in side elevation of the mechanism of Fig. 1.

Fig. 6 is a fragmentary view in vertical section taken along lines 6—6 of Fig. 5.

Fig. 7 is a fragmentary view in horizontal section taken along the line 7—7 of Fig. 5.

Fig. 8 is a fragmentary view in horizontal section taken along the line 8—8 of Fig. 5.

Fig. 9 is a fragmentary horizontal section taken along the line 9—9 of Fig. 5.

Figs. 10, 11 and 12 are complementary detail views in perspective of the mounting and suction supply members for each suction head, portions of these members being cut away in the views for purposes of illustration.

Fig. 13 is a fragmentary view in vertical section taken substantially along the line 13—13 of Fig. 6.

Fig. 14 is a fragmentary vertical section taken substantially along the line 14-14 of Fig. 6.

Fig. 15 is a fragmentary view in vertical elevation of the stamp supporting and stripping blocks mounted at the bottom of the stamp magazine.

Figs. 16, 17, 18 and 19 are fragmentary views illustrating the operation of the means controlling the connection between the vacuum source and the suction heads, Figs. 18 and 19 being sections taken along the lines 18-18 and 19-19 of Figs. 16 and 17 respectively.

Figs. 20 and 21 are fragmentary views in elevation illustrating the operation of the suction heads in removing stamps from the magazine and depositing them on the feed table.

Fig. 22 is a fragmentary view in vertical elevation taken substantially along the line 22-22 of Fig. 1, with a portion of the stamp supplying magazine and one suction head being broken away for purposes of illustration.

As shown in the drawings, the frame or base of the machine is provided with an upstanding web 2 (Figs. 1, 3 and 5) to which is secured as by screws 4 the rear wall plate 6 of a hopper or magazine 8. The hopper 8 comprises in addition to the rear plate 6 a pair of plates 10 generally L-shaped in cross section and secured to the opposite vertical edges of the plate 6 as by the screws 12. The plates 10 form the sides and the open front wall of the magazine 8. The inner wall surface of the rear plate 6 is tapered or bevelled inwardly as at 14 to facilitate the manual insertion of relatively elongated stamps, labels or similar strips such as may be desired to apply to articles or packages. The inner surfaces of each inwardly directed flange 16 of the plates 10, which flanges form the open front of the magazine, in a downward direction tapers outwardly as shown in Fig. 2 to permit outward deflection of a flexible strip 18 secured to the flanges 16 adjacent the upper edges as by rivet 20. The strips 18 provide deflectable wall surfaces for accommodating stamps which vary in width within the usual tolerances permitted in the production of such stamps so that the stamps of greater width will not be marred or torn when being moved between two unyielding surfaces spaced apart a distance less than the width of these wider stamps, and at the same time means are provided for preventing sidewise shifting of the stamp in the stack within the magazine. The strips 18 also provide means for yieldably mounting a pair of stamp supporting blocks 22 riveted or otherwise secured to the lower edges of the strips 18. Each of the blocks 22 is urged in an inward direction by a coil spring 24 acting on the block 22 through a bowed strip 26 secured or fulcrumed at its upper end to a flange 16 by a pin 28 and pressing at its lower end against the block 22. Each spring 24 is carried by a pin 30 passing through the strip 26 and secured to the flange 16, the spring 24 being interposed between the strip 26 and a tension adjusting screw 32 on the pin 30. A similar pair of stack-supporting blocks 34 are rigidly secured to the bottom of the rear wall plate 6 as by screws 36 and are aligned with the stack-supporting blocks 22. The inner surfaces of the stamp-supporting blocks 22 and 34 are serrated as at 38 to facilitate bowing of the end portions of the bottom stamp under the action of the stamp withdrawing means as seen in Fig. 20, to cause fluttering of a second stamp in the stack which, during withdrawal of the bottom stamp may tend to adhere to the latter, thereby to break the second

stamp loose from the stamp being withdrawn and to retain the loosened stamp in the magazine as shown in Fig. 16 until the stamp withdrawing means again reaches a position to withdraw such stamp from the magazine.

The hopper or magazine is also provided with a pair of auxiliary stack-supporting pins comprising pointed set screws 40 (Fig. 22) adjustably mounted in the side forming flanges of the plates 10 a given distance above the blocks 22 and 34. The set screws 40 are held in adjustable position by clamp nuts 42. The pointed ends of the pins or set screws 40 project between the ends of certain adjacent ones of the stamps in the stack and support the stack of stamps thereabove. The weight of the stack of stamps above the pins 40 causes the stamps immediately above the pins to sag centrally as shown in Fig. 22, and as stamps are withdrawn from below the pins, the weight of the stamps causes these sagging stamps to pass the pins 40. The pins 40 also act to prevent the application of the weight of the stack to the opposite end portions of the stamps below and thereby facilitate bowing of the opposite end portions of the bottom stamp when the same is withdrawn from the magazine.

The stamp withdrawing or removing means preferably comprises a pair of suction heads or blocks 44 (Figs. 1, 4, 5, and 20 to 22) the blocks having concave upper stamp engaging surfaces 46 (Fig. 5) and being spaced apart to engage the opposite end portions of the stamps as seen in Figs. 4 and 22. The suction heads 44 are mounted on the outer ends of parallel levers 48 which at their opposite ends are journalled on a stud shaft or bolt 50 (Figs. 1 and 5) and secured to operating yoke 52, also journalled on the stud shaft or bolt 50. The stud shaft 50 is mounted in a boss 54 (Fig. 1) formed on the web 56 of the frame portion 58. The yoke 52 is oscillated to move the suction heads between the stamp feed magazine 8 and a stamp receiving and guiding plate 60 (Figs. 1, 3, 5, 6, 7, 8, 13, 14 and 21) by an operating link 62 (Fig. 5) driven by any suitable and convenient mechanism in proper time relation to the feeding mechanism subsequently to be described, which feeds the stamps along the plate 60.

Air is supplied to and withdrawn from the vertical openings 64 in each suction head through a transverse port 66 in the suction head and a longitudinally extending port or passage 68 (Figs. 10 and 22) in its mounting lever 48. The longitudinal port or passage 68 at its inner end communicates with a transverse suction port or passage 70 and by a vertical passage 72 with a transverse suction breaking port or passage 74. Connection of the suction port 70 to a vacuum pump or vacuum source not shown and the connection of the suction breaking port or passage 74 to the atmosphere is controlled by a valve mechanism 76 (Fig. 11) which comprises a lever 78 (Figs. 1, 5, 11 and 16 to 19) extending parallel to each lever 48 and interposed between its associated lever 48 and a connecting block 80 to which the source of vacuum is connected as by the flexible pipe or tube 82. Each lever 78 is journalled at one end on the stud shaft 50 and adjacent its other end is provided with a transverse port or passage 84 (Figs. 11, 18 and 19) which when the lever 48 is moved to the position shown in Fig. 18 connects the suction port 70 to the port or passage 86 which latter port is connected to the suction pipe 82 by the port or passage 88. The connecting block 80 is mounted on the spaced pins 90

carried by the lever 48 which pins are spaced apart a sufficient distance to receive therebetween the valve lever 78 and to permit the required movement of this valve lever relative to the lever 48. The valve lever 78 is frictionally held against movement relative to the lever 48, thereby to cause the valve lever to move with the lever 48 during the movement of the latter by coil springs 92 (Figs. 1, 18 and 19) embracing the pins 90 and interposed between the outer face of the connecting block 80 and washers 94 held on the pins 90 by the cotter pins 96 (Figs. 5, 17 and 18).

Relative movement between each valve lever 78 and its associate lever 48 to position the levers as shown in Fig. 19, wherein the suction breaking port 74 is connected to atmosphere by the space between the lever 48 and the block 80 below the valve lever 78, is effected by an adjustable stationary set screw or bolt 98 (Figs. 5 and 16) which, as the lever 48 approaches its lower limit of movement, engages a depending lug 100 formed on the valve lever 78 (Figs. 5, 11 and 16). The screw 98 is carried by a plate or bracket 102 secured to or formed upon a post or bar 104 secured to any suitable fixed portion of the machine frame. Each valve lever 78 is also provided with an upwardly projecting lug 106 which is adapted to engage an adjustable stationary set screw or bolt 108 (Fig. 17) as its associate lever approaches its upward limit of movement to cause relative movement between these levers to bring them into the position shown in Fig. 18, wherein as previously described the suction port 70 is connected by the valve port 84 and the ports in the connecting block 80 to the suction intake pipe 82. The controlling set screw 108 for the valve lever 78 shown at the lower portion of Fig. 1 is carried by the inwardly turned end 110 (Figs. 1 and 17) of the post 104, while the controlling set screw for the other valve lever 78 is carried by the bracket 112 fastened to the web 56 of the machine frame.

Cooperating with the suction heads 44 to withdraw the lowermost stamp from the stack are a stamp-straightening and stack supporting bar 114 and stack supporting fingers 116 (Figs. 1, 3, 4, 5 and 22). The stamp straightening and stack supporting bar 114 moves upwardly and downwardly with the suction heads 44 and for that purpose is secured at one end to the operating yoke 52 as by a mounting screw 118 and an adjusting set screw 120 carried by the bar 114, so that the bar may be adjusted relative to the yoke properly to position the opposite end of the bar relative to the aligned concave surfaces 46 of the suction heads. The lowermost stamp both by reason of the weight of its unsupported portion between the opposed sets of supporting blocks 22 and 34 and by reason of the weight of the superposed stack of stamps tends to sag. It requires a much greater force to effect the bending or bowing of an elongated stamp or strip which is cuved or bent longitudinally than is required to bend or bow a stamp which lies flat in a longitudinal plane. Therefore such sagging of the stamp tends to prevent the withdrawal of the stamp under the action of the concave suction heads. When the suction heads 44 are brought to their uppermost position to engage the opposite end portions of the lowermost stamp of the stack, the free end of the bar 114 engages the stamp to be withdrawn at its center as shown in Fig. 22 to straighten this stamp and to support the stack during the time that the opposite end portions of the stamp are being sucked into en-

gagement with the concave surfaces of the suction heads.

The stack supporting fingers 116 project inwardly from opposed bars 122 (Figs. 3, 5 and 22), extending vertically on opposite sides of the magazine 8, each bar 122 being adjustably mounted within an elongated recess or groove 124 (Fig. 3) of a lever 126. The levers 126 are secured at their upper ends to stud shafts 128 and 130 (Figs. 1, 3 and 5), journaled in bosses 132 formed on the web 2 of the machine frame. The shafts 128 and 130 are interconnected for simultaneous oscillation in opposite directions by a link 134 (Figs. 1 and 3) pivotally secured at its opposite ends to oppositely extending cranks 136 and 138 secured respectively to the stud shafts 128 and 130. Operation of the shaft 130 and consequent simultaneous operation of the shaft 128 is effected by driven link 140 pivotally connected to the outer end of a crank 142 secured to the shaft 130, the link being driven by any suitable mechanism in proper timed relation to the link 62 (Fig. 5) so that the stack-supporting fingers 116 will be moved inwardly to project between the concave end portions of the stamp being withdrawn and the next stamp in the stack as shown in Fig. 4, thereby to remove the weight of the stack from the stamp being removed to insure that the lowermost stamp will be withdrawn by the suction head and to prevent withdrawal of a second stamp which might tend to adhere to the stamp being withdrawn in a region between the suction heads.

It should be noted that in being withdrawn from the stack, the stamps pass across the serrated surfaces 38 of the stack-supporting blocks 22 and 34, and these serrated surfaces will cause the edges of the stamps to flutter, which fluttering action will separate the upper stamp from a lower stamp if the opposite ends of two stamps are simultaneously sucked onto the suction heads so that the stack-supporting fingers pass between the second and third stamps of the stack, rather than between the first and second stamps of the stack. The serrated surfaces also, following separation of the second stamp from the stamp being properly fed, by engagement with the edges of the stamp (as shown in Fig. 15) retain the second stamp in position between the sets of stamp-supporting blocks 22 and 34 so that upon the next upward movement of the suction heads, this stamp will be withdrawn.

In moving downwardly with the suction heads 44, the stamp straightening bar 114 remains in engagement with the central portion of the stamp, thereby maintaining the stamp flat or straight during this movement of the stamp from the stack to the stamp receiving and guiding plate 60, and preventing the sagging of the stamp and the consequent release from the suction heads. The bar 114 as it moves downwardly passes at its forward edge through a recess 144 (Figs. 1, 7 and 8) in the forward edge of the plate 60.

The suction heads 44 and the bar 114 deposit the stamp on an upper surface of the plate 60 in the path of movement of a pair of pusher bars or feed fingers 146 (Figs. 1, 5, 7, 8 and 13). The pusher bars 146 are slidably received in grooves 148 in the plate 60 and are secured at their rear ends to a boss 150 formed on a slide block 152 (Figs. 1 and 22) slidably mounted on fixed bars 154 and 156. The slide block 152 is provided with a depending bifurcated portion or arm 158 (Figs. 5 and 22) between the furcations of which is re-

ceived a slide block 160 pivotally secured to the upper end of an operating lever 162 driven by any suitable mechanism in proper timed relation to the lever 62 so that immediately following the depositing of a stamp on the plate 60 by the suction heads 44, the forward feeding movement of the pusher bars 146 will be initiated.

The plate 60 forms the top wall of a glue pot 164 (Figs. 1, 3, 5, 6, 7, 8, 13 and 14) providing spaced chambers 166 connected by a cross chamber 167, for receiving a supply of adhesive to be applied to the stamps by rollers 168 secured to the shaft 170 journaled in the opposite side walls 172 and connected by the conventional coupling 174 to a continuously driven shaft 176, the shaft 170 being driven at such a predetermined speed that the peripheral speed of the glue applying rollers 168 is substantially equal to the speed at which the stamps are fed forwardly by the pusher bars 146 and onto these glue rollers. Each glue roller 168 is provided with an annular groove 178 forming axially spaced peripheral portions for a purpose which will presently appear.

A scraper 180 (Figs. 7, 8, and 14) for each glue roller provides forwardly and downwardly projecting portions 182 receiving the glue roller therebetween to remove the adhesive from the side surfaces of the roll. Forwardly projecting lug 184 is received in the annular groove 178 of the glue roller and the forward edges of the scraper between the lugs 182 and 184 are in close juxtaposition to the periphery of the glue roller so as to remove any excess adhesive from the peripheral surfaces of the roller and to determine the thickness of the adhesive film applied by the roller to the stamps. The scrapers 180 are mounted on sleeves 186, of which one only is shown in the drawings, secured to a shaft 188 journaled in the opposed side walls 172 of the glue pot, which shaft is provided externally of the glue pot with an adjusting crank 190 through the outer end of which passes a pin 192 carrying a thumb screw 194 by which the crank 190 may be adjusted upwardly and downwardly with the pin 192, the coil spring 196 retaining the crank in adjusted position. By adjustment of the thumb screw 194 the scraper blades may be moved toward and from the glue roller, thereby to predetermine the thickness of the adhesive coating applied by the rollers 168.

The glue pot 164 is provided with the cover plates 198 pivotally mounted on the common pin 200 carried by a bracket 202 secured to the web 2 of the machine frame. The cover plates extend from the pin forwardly over the plate 60 and about the periphery of the glue rollers and in covering relation to the outer end walls 204 of the glue pot (Figs. 5 and 14). The outer vertical wall 206 of each cover 198 is provided with a laterally extending projection 208 carrying an adjustable set screw 210 which is adapted to engage the forward wall 204 of the glue pot to space the cover a desired distance from the plate 60 and the wall 204 about this portion of the periphery of the glue roller.

The under surface of each cover 198, particularly in the region of the curved portion 211 (Fig. 5), is provided with grooves 212 as shown in Fig. 6 overlying the axially spaced peripheral portions of the glue roller so that the cover may be adjusted in relatively close juxtaposition to the surface of the glue roller and thereby maintain each stamp in engagement with the glue roller, while at the same time having the sur-

face of the cover overlying the adhesive carrying surfaces of the glue roller spaced therefrom such a distance that adhesive will not be applied to or collect upon the cover plate.

5 The pusher bars or feed fingers 146 in conveying the stamps from the suction heads 44 to the gluing mechanism pass through slots 214 in the covers. A plate 216, fastened to a web 218 of each cover and to the inner edge of the cover, 10 serves to augment the guiding action of the cover plate 198.

From the pusher bar 146 each stamp is received and fed in an arcuate path past the glue rollers by a pair of star wheels 220 (Figs. 3, 6, 7 and 13), secured to the shaft 170 and driven thereby at substantially the same peripheral speed as the rollers 168. The stamps will therefore be fed in this arcuate path without movement relative to the periphery of the glue rollers so that there will be no retarding or speeding up of the stamps by the glue rollers, and there will be no piling up of adhesive adjacent one or the other edge of the stamp or any flowing of the adhesive around an edge of the stamp onto its outer surface. The pusher bars 146 feed the stamps to a position on the plate 60 in the path of movement of the radially projecting lugs 222 of the star wheels 220, the plate 60 being slotted to permit the star wheels 220 to pass therethrough and engage the stamps in the plane of the upper surface of this plate. The star wheels 220 are mounted within a separate chamber formed in the glue pot between the adhesive reservoirs 166 (Fig. 6) and it should be noted that 25 the central portion of the plate 60 forms the top wall of this compartment to support and guide the stamp during its feeding movement to the star wheels and to the forward wall portion 223 (Fig. 3) along which the stamp is fed vertically by the star wheels. The covers 198 also overlie the star wheels 220 in spaced relation to the plate 60 and are recessed to receive the feeding lugs 222 of the star wheels. The star wheels 220 feed the stamps into the path of movement of a 30 pair of vertically shiftable pusher bars or feed fingers 224 (Figs. 3, 5, 7, 8, 13 and 14), which pass through slots 226 in the outer end walls of the covers 198 and grooves 228 in the outer end walls 204 of the glue pot to move the stamps from the star wheels 220 along a path extending tangentially to the peripheries of the glue rollers 168. The pusher bars or feed fingers 224 are secured at their upper ends to an arm 230 (Figs. 1, 3 and 5) in turn secured to a block 232 as by 35 an angle iron 234, the block 232 being in turn fastened to an operating rod 236 slidably mounted in the spaced horizontal arms 238 of the bracket 240 fastened to the web 2 of the machine frame. In order to prevent swinging of 40 the arm 230, the block 232 extends rearwardly from the rod 236 and adjacent its rear end carries a guide rod 242 slidably mounted in the arms 238 of the bracket 240. The rod 236 is driven by any conventional mechanism in proper timed 45 relation to the pusher bars 146 and the star wheels 220 so as to engage each stamp as it reaches the end of its arcuate path under the feeding action of the star wheels 220. The pusher bars or feed fingers 224 move each stamp 50 from the gluing mechanism onto a package feed table 244 (Fig. 14) between an advancing package 246 and a pair of laterally spaced blocks 248 between which the advancing package is fed, the blocks 248 thereby acting to press the stamp into 55 adhering engagement with the end of the pack-

age and to fold the ends of the stamp into adhesing engagement with opposed sides of the package.

The operation of the illustrated stamp feeding and gluing mechanism will be apparent from the foregoing description. Such operation may, however, be briefly summarized as follows:

As the suction heads 44 are moved upwardly and downwardly to withdraw the lowermost stamp from the stack of stamps in the magazine 8, the horizontal pusher bars or feed fingers 146 move forwardly and backwardly to feed the previously withdrawn stamp to the star wheels 220. When the suction heads 44 reach their lowermost position and deposit the withdrawn stamp on the receiving and guiding plate 60, the pusher bars 146 move forwardly from their rear-most position to engage and feed the stamp to the star wheels 220 as previously stated. During upward and downward movement of the suction heads, the adjustable screws 98 and 108 engage the lugs of the valve levers 78 and cause relative movement between these valve levers and the levers 48 so as to connect the suction heads to the source of vacuum when the levers 48 reach their upper position and to connect the suction heads to atmosphere when the levers 48 reach their lower positions.

The lugs 222 of the star wheels 220 engage the stamps and feed them in an arcuate path concentric to the axis of the glue rollers and at a speed substantially equal to the peripheral speed of the glue rollers so that during application of adhesive to the stamps, there is no relative movement between the stamps and the glue rollers. It should be noted that the stamps are fed to the glue rollers along a path extending tangentially to the peripheries of the glue rollers so that there will be no warping of the stamps by the rollers, nor accumulation of excessive adhesive at the forward edges of the stamps. As the star wheels move the stamps about the arcuate path concentric to the axis of the glue rollers, the vertical pusher bars or feed fingers 224 descend and feed the stamps from the star wheels along a vertical path tangentially to the peripheries of the glue rollers and onto a table 244 along which packages 246 are advanced to receive the stamps. The manner in which the stack-supporting and stamp-straightening bar 114 and the stack-supporting fingers 116, the serrated stack-supporting blocks 22 and 34 cooperate with the concave heads 44 to insure the withdrawal of a stamp upon each downward movement of the suction head and to prevent withdrawal of more than one stamp at a time from the magazine 8 has been previously described and need not be repeated.

Changes may be made in the form, construction and arrangement of the parts without departing from the spirit of the invention or sacrificing any of its advantages, and the right is hereby reserved to make all such changes as fairly fall within the scope of the following claims.

I claim:

1. In a mechanism for applying stamps or similar labels to articles, an adhesive applying roll, means for driving said roll, means for feeding stamps to said roll into engagement with the peripheral surface thereof, and mechanism including means engageable with the stamp edges for positively feeding the stamps in an arcuate path while in engagement with the roll and at the peripheral speed of the roll.

2. In a mechanism for applying stamps or

labels to articles, an adhesive applying roll, means for driving said roll, means for feeding stamps into engagement with the periphery of said roll, means including a rotary member having a radially projecting portion engageable with an edge of a stamp fed to the adhesive applying roll for feeding the stamp in an arcuate path defined by the periphery of the roll, and means for driving said rotary member so as to drive said radially projecting portion at a speed substantially equal to the peripheral speed of the adhesive applying roll during engagement of the stamp therewith.

3. In a mechanism for applying stamps or labels to articles, an adhesive applying roll, a cover for said roll, means for feeding stamps to said roll, said cover cooperating with said feeding means for maintaining stamps in engagement with the peripheral surfaces of the roll during their feeding with the roll, said cover having portions laterally disposed with respect to the roll lying substantially in the cylindrical surface defined by the periphery of the roll, and having a recess overlying the periphery of said roll for preventing the accumulation of adhesive on the inner stamp guiding surface of the cover.

4. In a mechanism for applying adhesive to stamps or similar labels, a glue pot comprising an adhesive reservoir, an adhesive applying roll operable to receive adhesive from said reservoir, spaced stamp-guiding plates engageable with opposite faces of the stamps, means forming a cover for said roll to maintain the stamps in engagement with the roll, the guiding surfaces of said plates extending arcuately substantially in the cylindrical surface defined by the periphery of said roll, means for feeding stamps into engagement with the roll and between said spaced guiding plates, means for driving said roll, and means for feeding said stamps in the arcuate path defined by said guiding plates at a speed substantially equal to the peripheral speed of the roll.

5. In a mechanism for feeding and applying stamps or the like to articles, means for feeding the stamps along a substantially horizontal path, an adhesive applying roll, the periphery of which is tangential to said horizontal path, means for driving said roll, a second feeding means receiving the stamps from the first feeding means for feeding the stamps about the periphery of the roll at the peripheral speed of the roll, and a third feeding means for feeding the stamps from the second feeding means along a vertical path tangential to the periphery of the adhesive applying roll to the articles to which they are to be applied.

6. In a mechanism for feeding and applying stamps or the like to articles, a stamp receiving and guiding plate, a stamp feeding finger slidable along said plate, an adhesive applying roll adjacent to said plate, means for driving said roll, a rotary member having a radial projection operable through a slot in said stamp receiving and guiding plate, said rotary member receiving the stamps from said stamp feeding finger, means for driving said rotary member to cause the radial projection to engage the stamps received by said member and feed the stamps about the periphery of the roll, said stamp receiving and guiding plate having an arcuate portion substantially within the cylindrical surface defined by the periphery of the roll, and a second stamp guiding plate having an arcuate portion also substantially within the cylindrical surface defined by the roll and spaced from the first stamp receiving

and guiding plate and cooperating with said first guide plate to maintain the stamps in engagement with the roll, and means for feeding the stamps from said rotary member and said roll.

7. In an adhesive applying mechanism for sheets and the like, an adhesive applying roll, means for driving said roll at a predetermined speed, sheet feeding means including a rotary member having a radially extending projection engageable with an edge of a sheet for positively feeding the sheet while it is in engagement with said roll, and means for driving said rotary member at a speed so that the sheet is fed by said projection at a speed substantially the same as the peripheral speed of said roll.

8. In an adhesive applying mechanism for sheets and the like, an adhesive applying roll, said roll being rotatable to apply adhesive to the sheets and said roll being provided with a circumferentially depressed channel, and a guide member arranged peripherally of the roll for maintaining the sheets in engagement with the roll, said guide member having a circumferentially extending and radially inwardly directed rib in alignment with the channel of said roll, the inwardly directed surface of said rib lying substantially within the cylindrical surface defined by the adhesive applying surface of said roll.

9. In an adhesive applying mechanism for sheets and the like, an adhesive applying roll, said roll being rotatable to apply adhesive to the sheets and said roll having an adhesive applying surface and a recessed portion, and a guide member arranged peripherally of the roll for maintaining the sheets in engagement with the roll, said guide member having a surface in axial alignment with the adhesive applying surface of the roll and a surface in axial alignment with the recessed portion of the roll, the last named surface of the guide member lying substantially within the cylindrical surface defined by the adhesive applying surface of the roll.

10. In an adhesive applying mechanism for sheets and the like, an adhesive applying roll, means for driving said roll at a predetermined speed, sheet feeding means engageable with the sheets for feeding them across the face of said roll, a pair of spaced guide plates associated with the roll and between which the sheets are propelled by the sheet feeding means, said plates being engageable with the opposite faces of the sheets for maintaining the sheets in operative engagement with the sheet feeding means and with said roll, and means for driving said sheet feeding means so as to propel the sheets at a speed substantially the same as the driven peripheral speed of said roll.

11. In an adhesive applying mechanism for sheets and the like, an adhesive applying roll, having an adhesive applying surface, means for driving said roll at a predetermined speed, sheet feeding means having an operative feeding element engageable with the sheets for feeding them continuously while they are in engagement with

said roll, a pair of spaced guide plates between which the sheets are fed engageable with the opposite faces of the sheets for maintaining the sheets in operative engagement with said elements and with said roll, and means for driving said feeding element at a speed substantially the same as the driven speed of the adhesive applying surface of said roll, one of said guide plates being substantially coincident with an extension of the adhesive applying surface of said roll and with the cylindrical surface defined by the path of travel of said operative feeding element of said feeding means.

12. In an adhesive applying mechanism for sheets and the like, an adhesive applying roll, means for driving said roll at a predetermined speed, sheet feeding means engageable with the sheets for feeding them continuously while they are in engagement with said roll, a pair of spaced guide plates between which the sheets are fed engageable with the opposite faces of the sheets for maintaining the sheets in operative engagement with the feeding means and with said roll, and means for driving said feeding means so as to propel the sheets at a speed substantially the same as the driven peripheral speed of said roll, the first of said guide plates lying substantially within the cylindrical surface defined by the periphery of the roll, and the other of said plates being adjustable with respect to said first plate.

13. In an adhesive applying mechanism for sheets and the like, means for feeding the sheets along a predetermined path of travel, a pair of coaxially mounted adhesive applying rolls disposed along the path of travel of the sheets and engageable therewith, and said sheet feeding means including a pair of rotatable members coaxially mounted with the adhesive rolls and provided with radially extending projections engageable with the edges of the sheets for propelling them along their path of travel.

14. In an adhesive applying mechanism for sheets and the like, means for feeding the sheets along a predetermined path of travel, a pair of coaxially mounted adhesive applying rolls disposed along the path of travel of the sheets and engageable therewith, said sheet feeding means including a pair of rotatable members coaxially mounted with the adhesive rolls and provided with radially extending projections engageable with the edges of the sheets for propelling them along their path of travel, a pair of spaced guide plates associated with the rolls and engageable with the opposite faces of the sheets for maintaining the sheets in operative engagement with the feeding means and said rolls, and said feeding means also including a pair of reciprocating fingers engageable with the sheets for moving them along their path of travel.

15. A mechanism as defined in claim 1, wherein said means engageable with the stamp edges comprises a rotary member coaxially mounted with said roll.
